UNITED STATES PATENT OFFICE

JOSEPH DUGAN, OF LOS ANGELES, CALIFORNIA

CONTINUOUS AIM GUNFIRE CONTROL SYSTEM

Application filed May 25, 1932. Serial No. 613,489.

The invention forming the subject matter of this application is a fire control system adapted for use on unstable platforms such as the deck of battleships, the chassis of railroad guns, tanks, etc. to eliminate the effect 5 of roll and pitch of the platform on the train and elevation settings of the gun or guns mounted on such platforms to rotate about the usual train and elevation axes.

The object of the present invention is to 10 provide such guns with control mechanism for maintaining the guns continuously corrected in train and elevation for the "trunnion tilt" error caused by rolling and pitching of the platform, regardless of the position or movements of the target in space relative to the gun.

Other objects of the invention will become apparent as the detailed description thereof 15 proceeds.

In the drawings:

Figures 1, 2, 3 and 4 are mathematical diagrams explanatory of the system involved in the present invention;

Figure 5 is a view, partly in side elevation and partly in central vertical section, disclosing the arrangement of the essential elements of the mechanism forming the gun director of this system;

Figure 6 is an end elevation of the director shown in Figure 5, parts of the mechanism being broken away and shown in section to illustrate the details of construction;

Figure 7 is a horizontal section taken on line 7-7 of Figure 5;

Figure 8 is a plan view of the corrector mechanism forming part of the aforesaid gun director, parts being broken away to show details of construction;

Figure 9 is a fragmentary detail in elevation of part of the fire control elements of the director;

Figure 10 is a wiring diagram illustrating the connection between the follow-up motors forming part of the director and a two-part commutator for controlling said motor; and

Figure 11 is a diagram illustrating generally the type of gun adapted to be controlled by the director illustrated in Figures 5 to 10.

Before describing the director mechanism in detail, it will be necessary to discuss the mathematical principles upon which the system is based. These principles are illustrated in Figures 1 to 4, inclusive; and the symbols used therein to designate the various angles and their mutual relation have the meanings attributed to them in the following table:

A—angle of elevation between a horizontal line, in the vertical plane of sight to the target, and the line of sight;

de—vertical angle of depression between a horizontal line, in the vertical plane of sight to the target, and the line of sight;

s—vertical angle (super-elevation) between the line of sight and the bore axis of the gun;

e—angle of elevation of the gun relative to the horizontal in the vertical plane of sight to the target;

P—vertical angle of the deck to the horizontal in the vertical plane of sight to the target;

R—angle of roll of the deck in a plane perpendicular to the deck and perpendicular to the vertical plane of sight to the target at any angle of pitch;

E—angle of elevation of the gun in the vertical plane of sight to the target, relative to the deck and uncorrected for cross roll *R*;

Ec—angle of elevation of the gun in a plane perpendicular to the deck corrected for cross roll *R*;

T—angle of correction of the gun in train in the plane of the deck from the vertical plane of sight to the target, to correct for error due to cross roll of the deck through the angle *R*;

Dg—angle of lateral deflection of the gun bore axis relative to the vertical plane of sight to the target;

D—angle of lateral deflection of the vertical plane containing the bore axis of the gun and set-off in a horizontal plane relative to the vertical plane of sight to the target;

Dd—angle of deflection of the gun in the plane of the deck relative to the vertical plane of sight to the target.

In this system the terms "pitch" and "roll" 100

have broader meanings than are applied to them in seaman's language. The axis of roll lies constantly in a plane parallel to the gun deck and in the vertical plane of sight to the target passing through the intersection of the train and elevation axes of the gun, regardless of the pitch of the deck in the plane of sight, and regardless of any lateral deflection of the gun relative to the vertical plane of sight to the target.

The expression "vertical plane of sight" is used for convenience in referring to the vertical plane passing through the target and the point of intersection of the train and elevation axes of the gun. It is contemplated that the guns controlled by this director system may be fired at targets invisible to persons operating the guns; as for example, at targets obscured by a smoke screen or by a mountain range, etc. In this case, it would be necessary to set the director and the guns by compass, by sighting at some object known to lie in the vertical plane through the target and the intersection of the gun axis, or by some other means of determining the direction of the target from the gun or guns.

The diagram shown in Fig. 1 is intended to illustrate the necessity for considering the angles of altitude and depression of the target relative to a horizontal line in the vertical plane of sight, in order to determine the angle e of elevation of the gun bore axis relative to the said horizontal line. As shown in Figure 1, the horizontal line OT₂ is taken as the horizontal line of reference in the vertical plane of sight to the target, and the distance OT₂ is considered as the maximum horizontal range of a gun positioned at the point O and elevated so that the trajectory of a shell fired therefrom will pass through the target T₂. It will be evident from Figure 1, that the altitude A of the target T₂ above the horizontal line is zero. It will also be evident that the angle e indicates the angle which the bore axis of the gun makes with the said horizontal line of reference. In this case the angle e is equal to the angle of the superelevation S₂.

The same angle of gun elevation e relative to the horizontal would be necessary in firing at targets T₁, T₃, and T₄ lying on the trajectory of the gun positioned at the point O and elevated for maximum range. The target T₁ is evidently depressed below the horizontal reference line through the angle de while the line fire or angle e remains the same as before. In this case, it is evident that the superelevation angle is equal to S₁.

In the case of the target T₃, the altitude is A₃ while the angle of superelevation is S₃. Similarly the angle of superelevation of the gun aimed at the target T₄ is the angle S₄, and the altitude of the target of the angle A₄.

It is evident, then, that it is necessary to take into consideration the altitude or de-

pression of the target relative to the horizontal line of reference in the vertical plane of sight to the target in order to determine the line of fire of the gun; that is, to determine the angle of elevation e of the gun bore axis relative to the said horizontal reference line. The target T₅ is illustrated in Figure 1 as located at the same range from the gun as the target T₄; but the target T₅ lies in the horizontal plane and the trajectory for target T₅ is different from the trajectory for target T₄ and much less curved and a different angle of gun elevation relative to the horizontal line is required. The angle of gun elevation for target T₅ would also be required for any target lying in the trajectory of target T₅; as, for example, the target T₆ lying in the line of sight depressed through depression angle De in the vertical plane of sight to the target.

This discussion of the matter illustrated in Figure 1 is interpolated here to emphasize the fact that although the altitude angle may be determined from the stabilized sight forming a part of the director disclosed herein, it is not essential to use the director sight for this purpose. The angle of altitude is usually determined by an altimeter connected with the range finder. The angle of superelevation must be determined in connection with the angles of altitude or depression before it can be introduced into any corrector system.

The angle e includes all angles measured in the vertical plane of sight relative the horizontal in that plane. This, of course, includes altitude, sight depression, vertical prediction and ballistic correction angles, etc.; and constitutes one of two settings of an ideal gun, forming part of this system, relative to a plane representing the horizontal plane of reference. The algebraic sum of this angle e and the pitch angle P, give the setting E of the ideal gun relative to the deck, and in the vertical plane of sight to the target.

Figures 2, 3 and 4 are vector diagrams in which the vectors designated by the characters E, E_c, T and D_g are to be considered as segments of arcs of great circles lying on a sphere having its center at the point O in each diagram. These vectors represent elements in the corrector part of the director disclosed herein and the vectors corresponding to said elements are designated by similar reference numerals underscored.

Figure 2 is a vector diagram of a general type in which deflection of the target from a vertical reference plane is taken into consideration. The director mechanism includes a mechanical replica of the vector diagram shown in Figures 2, 3 and 4, and mechanically solves the equations (1), (2), (3) and (4) shown in the drawings below Figures 2 and 4.

In Figure 2, the angles K and α are auxiliary angles used in deriving the values of

the angles E_c and T when the angle E and D_g are given.

In accordance with the laws of spherical trigonometry:

- (a) $\sin D_g = \sin K \sin x$; or, $\sin x = \sin D_g / \sin K$
- (b) $\tan E = \tan K \cos x$; or, $\cos x = \tan E / \tan K$
- (c) $\tan x = \tan D_g / \sin E$; or, $\cos x = \sin E / \tan D_g$

$$\begin{aligned} \tan T &= \tan K(\cos 90 - (R + x)) = \\ &= \tan K(\sin R \cos x + \cos R \sin x) \\ &= \tan K \frac{\tan E}{\tan K} \sin R + \\ &\quad \frac{\tan E}{\cos x} (\sin x \cos R) \\ &= \tan E \sin R + \tan E \tan x \cos R \\ &= \tan E \sin R + \frac{\sin E \tan D_g}{\cos E \sin E} \cos R \end{aligned}$$

(1) $\tan T = \tan E \sin R + \sec E \tan D_g \cos R$

$$\begin{aligned} \sin E_c &= \sin K \sin(90 - (R + x)) = \\ &= \sin K(\cos R \cos x - \sin R \sin x) \\ &= \frac{\sin D_g}{\sin x} \cos R \cos x - \sin K \\ &\quad \frac{\sin D_g}{\sin K} \sin R \\ &= \sin D_g \cos R \cot x - \\ &\quad \frac{\sin D_g \sin R}{\tan D_g} \\ &= \sin D_g \cos R \frac{\sin E}{\tan D_g} - \\ &\quad \frac{\sin D_g \sin R}{\tan D_g} \end{aligned}$$

(2) $\sin E_c = \sin E \cos D_g \cos R - \frac{\sin D_g \sin R}{\tan D_g}$

Equations (a), (b) and (c) are fundamental equations used in spherical trigonometry, the solutions of which are obvious from inspection of the diagram in Figure 2; and are employed herein merely to facilitate the solution of the more complicated equations (1) and (2).

Figure 4 is a vector triangle in which the deflection angle D_g is zero. It will be evident from inspection of Figure 4, that the tangent of the angle of train correction T and the corrected angle E_c of elevation have the values shown beneath the figure. These equations (3) and (4) are clearly derivable from equations (1) and (2) when the value O is substituted for the angle D_g in each of the aforesaid equations (1) and (2).

It will be evident, too, from consideration of Figures 2 and 4, that when deflection D_g is zero and the line of fire is parallel to the deck that no correction in either train or elevation is necessary. This is a condition in which the deck rolls around the bore axis of the gun. This will also be evident from consideration of Figure 4 in which it is evident that if the arcuate line representing the deck be rolled about the point ab in the line

oab , no vector triangle will be generated. It is further evident that if the gun be depressed toward the deck, instead of elevated, the vector triangle representing this condition will be above the point ab in Figure 4, and to the right of the vertical reference plane VO_f ; the train and elevation corrections being effected in the opposite directions to the corrections necessary when the gun is elevated above the deck. This condition will also be evident from consideration of any of the equations (1), (2), (3) and (4) in which a negative angle E would give negative results for the angle T , and E_c .

In determining the angle of deflection for use in this system, and referring now particularly to Figures 2 and 3 of the drawings, it will be necessary to translate the deflection angle D_g of this line of fire in a plane perpendicular to the vertical plane of reference VO_d from its elevated position to the horizontal plane. The method of performing this translation is clearly indicated in Figure 3, in which the angle D indicates the angle of deflection in the horizontal plane of reference. This angle D is merely the projection on the horizontal reference plane of the angle D_g from its elevated position where the gun bore axis intersects the sphere. A continuation of this projection below the horizontal plane gives the angle of deflection D_d in the plane of the deck which is clearly shown in the drawing as depressed through the angle P below the horizontal reference plane.

Regardless of the position of the angle D_g either above or below the horizontal plane, it is necessary that its projection on the horizontal plane be determined so that it can be set in properly in the deflection part of the apparatus. For targets lying in the same horizontal plane as the gun, it is obvious that the deflection angle D may be determined in the usual manner.

It will be apparent from the foregoing discussion, that the system is intended to correct continuously the errors due to the roll and pitch of the deck, and to provide a means for setting the gun in train and elevation as if the director and gun were mounted on a stable horizontal deck or platform. It will also be evident that the system is designed to divorce the problem of trunnion tilt correction from the line of sight; and to consider this problem with reference to vertical and horizontal planes, regardless of the elevation or depression of the sight.

In Figures 2, 3 and 4, the vertical reference plane is indicated by the sector VO_d ; and Of indicates the horizontal reference line lying in said vertical plane. The arc cd is the angle of train correction T required to compensate for the error in gun train caused by the roll of the deck through the angle R about the axis $R'-R'$ lying in the plane of

the deck and in the vertical plane of sight VO_d . The arc bc is the corrected angle of elevation E_c required under the same conditions; and the arc ab is the angle of lateral deflection D_g of the gun bore axis to compensate for errors due to drift, change of position of the target during the time of flight of the shell, etc. The arc ad is the angle of elevation E of the gun relative to the deck, uncorrected for roll about the axis $R'-R'$.

As shown in Figures 5 to 10 of the drawings, the director comprises a pedestal 1, having a training table 2 mounted to rotate thereon about a train axis $X-X$ perpendicular to the unstable gun deck or platform. Standards 3 and 4 are secured to the table 2, on opposite sides of the axis $X-X$ and at substantially equal distances therefrom.

A gimbal ring 5 is pivoted to swing in said standards 3 and 4 about the common axis of the trunnions 6 and 7; and an inner gimbal ring 8 is pivoted to ring 5 by trunnions 9 and 10 having their common axis intersecting the axis of trunnions 6 and 7 at right angles. The ring 8 is channel shaped in cross section. A ring, or spider 12 is mounted to rotate in the channel 11 of ring 8; and has suitably secured thereto an arcuate bar 13 provided with a guide groove 14 for slidably receiving an antifriction wheel 15 at the end of a cylindrical rod 16 the axis of which represents the axis of an ideal gun. The bar 13 is perpendicular to ring 12 and is braced in this position by the side bars 17 and 18 secured at their lower ends to the said inner ring 12.

The ideal gun comprises a gear ring 19 rotatably mounted in an arcuate casing 20 supported by standards 21 and 22 on a deflection plate 23 mounted on the table 2 to rotate about the train axis $X-X$. The gear ring 19 is rotated about its center by means of the worm 24 secured to a shaft 25 journaled in the standards 26 and 27 also secured to the deflection plate 23 between the standards 21 and 22.

The rod 16 passes rotatably through an aperture 28 in the gear ring 19, and is connected at its inner end to an arcuate bar 29 having secured to its opposite ends the trunnions 30 and 31, representing the trunnions of the real gun. The trunnion 30 is journaled in the ring 12; and the trunnion 31 is connected to or forms a part of the rotor of elevation transmitter $E-T$ which has its stator fixed to the ring 12. The trunnions 30 and 31 have their common axis lying in the plane of the intersecting axes of the trunnions 6, 7, 9 and 10.

The channel ring 8 has arms 32 and 33 extending from its lower face inwardly to form a cup shaped support 34 for an electrical differential 35 of the well known "selsyn" type. The stator of differential 35 is fixed to the support 34; and its rotor 36 is fixed

to a cross bar 37 fixed to the lower ends of the brace bars 17 and 18.

The deflection plate 23 has an indicator arm 38 (see Fig. 5) extending radially therefrom to read against a deflection scale 39 formed on or fixed to the table 2. A screw-threaded stud 40 extends up from the indicator arm 38 and through the slot 41 formed in an arcuate bracket 42 (see Fig. 8) fixed to table 2. A clamping nut 43 threaded on stud 40 operates to clamp arm 38 in any desired position on bracket 42.

The ring 5 at its rear end has a chisel edge electrical contact member 44 suitably secured thereto and insulated therefrom. This member 44 extends around the ring 5 for twenty or thirty degrees on opposite sides of the axis of the trunnion 10. The edge of member 44 is designed to make contact with a contact 45 secured to a screwthreaded stud 46 which is mounted to slide in a slot 47 formed in an arcuate fire control scale member 48.

The member 48 is struck from the center of ring 5; and terminates at its lower end in a spacer block 49 separating the standards 50 and 51 (see Figure 9) fixed to the deflection plate 23. The shaft 25 extends through an aperture in the block 49 and terminates in a crank handle 52. A gun elevation scale plate 53 is fixed to shaft 25 to read against an indicator 54 secured to block 49. A clamp nut 55 serves to adjust and hold the contact 45 in any desired angular position on the arcuate member 48.

The trunnion 6 has a bevel gear 56 secured to the end thereof projecting through standard 3; and, this gear 56 meshes with a similar gear 57 secured to the rotor shaft 58 of a follow-up motor 59 which is secured to the side of standard 3. The trunnion 9 extending from ring 8 through ring 5 has a bevel gear 60 secured thereto; and this gear 60 meshes with a similar gear 61 fixed to a shaft 62 journaled in a bearing bracket 62' fixed to or formed integral with the ring 5.

The shaft 58 is connected by a universal joint 63 to the slotted cylindrical member 64, having another member 65 mounted to slide non-rotatably therein. The two members 64 and 65 constitute a telescoping shaft, and are prevented from relative rotation by means of the key 66 extending from member 65 to slide in the slot 67 of member 64.

The upper end of member 65 is connected by a universal joint 68 to a stub shaft 69 which is journaled in a bracket 70 suitably secured to a gimbal ring 71 forming part of the direction finder element of the director. The shaft 69 has its free end fixed to a bevel gear 72 meshing with a similar gear 73 fixed to a trunnion 74 extending through gimbal ring 71.

The shaft 62 (see Figure 5) is connected by a universal joint 75 to a member 76 slidably but non-rotatably mounted in a cylindrical

member 77 which is, in turn, connected by a universal joint 78 to shaft 79 of a follow-up motor 80. A key 81 fixed to member 76 slides in the slot 82 of member 77 to prevent relative rotation of members 76 and 77. The follow-up motor 80 is suitably bolted to the standard 83 which, with standard 84, forms the means for pivotally supporting the gimbal ring 71. Trunnions 85 and 86 extend from the ring 75 through suitable bearings in said standards 83 and 84 in the usual gimbal ring construction. The trunnion 85 has a bevel gear 87 secured thereto and meshing with a similar bevel gear 88 fixed to the end of the follow-up motor shaft 79.

A trunnion 89 cooperates with trunnion 74 in pivotally connecting the intermediate gimbal ring 90 to the ring 71. Trunnions 91 and 92 pivotally connect another inner gimbal ring 93 to the ring 90; and trunnions 94 and 95 serve to support the gyro 96 rotatably in the said gimbal ring 93.

A two part commutator 97 fixed to the inner ring 90, cooperates with a conducting wheel 98 rotatably mounted on the lower end of an arm 99 to control the operation of the follow-up motor 80 in the well known manner. The arm 99 is fixed to the trunnion 91, and is rotated thereby. A two part commutator 100 is fixed to the ring 93 to cooperate with a conducting trolley wheel 101, rotatably mounted on the lower end of an arm 102 depending from and fixed to the trunnion 95, in controlling the operation of the follow-up motor 59 in the corrector part of the director. There is nothing novel in these follow-up mechanisms, the wiring connections of which are shown diagrammatically in Figure 10.

The target sights 103—104 are mounted on a trunnion member 105 pivoted at its opposite ends in the sight standards 106 and 107 carried by the intermediate gimbal ring 90. Spirit levels 108 and 109 are mounted on the ring 90 for use in checking up the movements of the gyro, and to indicate the corrections necessary to restore the ring 90 to horizontal position when moved therefrom either by wandering of the gyro or other cause.

Any suitable levelling sight L and cross levelling horizon sight CL may be suitably supported on the ring 90 to serve the same purpose as the spirit levels 108 and 109 whenever it is possible to sight on the horizon or distant objects. The ring 93 and gyro 96 may be replaced by a weight suitably fixed to the ring 90. The absolutely essential requirement in this system is the maintenance of the ring 90 horizontal in the direction of the axis of trunnions 85 and 86 and also in the direction of the axis of trunnions 74 and 89. Whether this be effected by a common pendulum, a gyroscopic pendulum, horizon sights, or spirit levels, or all of these well known levelling devices is immaterial so far as the principle of this invention is concerned.

Figure 11 illustrates diagrammatically the type of gun adapted to be controlled by the director system disclosed herein. The gun 110 is mounted by its trunnions 111 and 112 to rotate about its elevation axis in the standards 113 and 114 extending up from the training table 115.

The table 115 is mounted to rotate on the support 116 suitably secured to the deck or unstable platform. A repeater T-R repeats the movements of the director train transmitter T-T modified, when necessary, by operation of the electrical differential or transformer 35. A follow-up motor T-M may be controlled by this repeater T-R to rotate the table 115 through gearing 117, 118 connected respectively to the rotor shaft of motor T-M and the table 115.

The gun may be rotated in elevation by gearing 119, 120 connecting the gun to the shaft of a follow-up motor E-M under the control of the elevation repeater E-R which is electrically connected to the elevation transmitter E-T of the director. The details of the follow-up mechanism are merely indicated in the drawing, since the invention is not concerned with any particular mechanism for training or elevating the gun. Any of the well known "follow-the-pointer", "zero reading" or "follow-up" train and elevation mechanisms may be used to control the elevation and train movements of the gun or guns.

The train transmitter is connected electrically through wiring indicated generally by the reference numeral 121 to the "selsyn" transformer 35; and wiring 122 connects the "selsyn" transformer 35 to the train repeater T-R at the gun. This train repeater controls a follow-up train motor T-M through the wiring 123 to operate the gearing 117 and 118 for rotating the gun in train. A two-part commutator (not shown) is fixed to the gear 124 of the train repeater and a pointer 125 rotatably over this commutator operates to control the direction of rotation of the shaft of the follow-up motor T-M. This method of follow-up control is old and well known in the art and is quite similar to that illustrated in Figure 10 of the drawings. The elevation correction Ec is transmitted from the elevation transmitter ET through the wiring 124 to the elevation repeater E-R at the gun. The elevation repeater controls a follow-up motor E-M in the usual manner to operate the elevation gearing 119, 119' and 120 and rotate the gun 110 in elevation about its trunnion axes 111 and 112.

The invention is not concerned with any particular wiring system and a direct current system of transmission may be used instead of the "selsyn" system for transmitting the train movements of the repeater T-T to the train repeater T-R at the gun. The transformer 35 merely acts as a sort of electrical differential to perform the same func-

tion as is performed by the repeater R-33 and transmitter T-4, in my United States Patent No. 1,733,531. A single transmitter may be substituted for the transformer 35, and 5 the train transmitter may transmit the change of bearing of the target directly to the train repeater at the gun. In this case, however, it will be necessary to interpose a differential between the transmitter substituted 10 for the transformer 35 in order that the train correction may be added algebraically to the train correction caused by change of bearing between the gun and target transmitted to the train repeater through the 15 same differential.

The corrector mechanism shown in Figures 5 and 6 operates as a mechanical computer to solve the Equations (1), (2), (3) and (4) and may be used separately from 20 any particular direction finder to determine the corrections necessary to eliminate trunnion tilt errors in any gun of the type shown in Figure 11 and mounted on an unstable platform.

25 The elements of the corrector mechanism corresponding to the vectors shown in Figures 2 and 4 have the same reference numerals as these vectors but without underscoring. For example, the arcuate member 13, shown 20 in Figures 5 and 6 corresponds to the vector E indicated in Figures 2, 3 and 4 by the reference numeral 13. The axis of roll R'-R' in the vector diagrams is duplicated in the corrector by the common axis 9-10 35 of the trunnions 9 and 10. The gimbal ring 5 in the corrector mechanism is represented in Figures 2, 3 and 4 by the arcuate line 5; and the gimbal ring 8 is represented in the vector diagrams by the numeral 8. The vector 40 Ec of the vector diagrams 2, 3 and 4 represents the position of the member 13 of the corrector after the ring 5 has been pitched downwardly from the horizontal through the angle P, and after the ring 8 has been rotated 45 about the axis of trunnions 9 and 10 through the angle R.

It will be seen from comparison of the vector diagrams with the mechanism illustrated in Figures 5 and 6 of the drawing, 50 that the member 13 rotates about the axis of rod 16 in the same manner as the vector Ec rotates about the point b in Figures 2 or 3, and about the point ab indicated in Figure 4, and that this point of rotation of 55 the member 13 or vector Ec coincides with the intersection of the axis of the roller 15 with the center line of the member 13. The ring 5 rotates about the gun axis of the trunnions 6 and 7, which is indicated in Figure 60 4 by a line to which the numeral 6-7 is applied. It will be apparent from comparison of Figures 2, 3 and 4 with the other figures of the drawing that the corrector shown in these other figures is a mechanical replica 65 of the vectors shown in Figures 2, 3 and 4,

and that this corrector will solve with mathematical accuracy all the problems of trunnion tilt correction which may be represented by vectors, as illustrated in the drawings.

The fire control mechanism illustrated in Figures 5, 8 and 9 is of peculiar importance in this system inasmuch as the contact 45 is moved laterally along with the deflection table 23 so that it can be set along the scale 125 to control the angle of elevation in the vertical plane of fire at which the gun may be fired. Since the contact 45 moves laterally around the gimbal ring 5, it is necessary that the cooperating contact 44 on the ring 5 be extended around said ring on opposite sides of the trunnion axis 10, in order that the contact may be made with contact 45 to control the instant of fire at any deflection setting of the gun.

It will be observed that the various arcuate members of the corrector mechanism are really segments of skeleton spheres having their center at the center of the gimbal system composed of the rings 5 and 8 supported upon the standards 3 and 4. The sight or direction finding part of the system is supported upon frame work 2' rigidly connected with the training table 2 and parallel to said table. It is not essential that the corrector part of the director be mounted so that the train and elevation axes of the ideal gun be perpendicular and parallel, respectively, to the deck. The corrector is in reality a computer which may be located in any position in space so long as the pitch and cross roll of the gun platform are properly applied to the respective axes 6-7, 9-10 in the corrector. The corrector may be placed side by side with the direction finding parts of the director, connected in tandem therewith, or located at a distance therefrom and operated by any suitable type of electrical transmission. From a mechanical standpoint, it is most convenient to connect it to the direction finder as shown in the drawings.

What I claim is:

1. An unstable platform, a sight, means for mounting said sight to pivot universally on said platform, a gun rotatable about train and elevation axes on said platform, means for simultaneously determining the pitch of the platform in the vertical plane of sight to the target and the roll of the platform in a plane perpendicular to said plane of sight and perpendicular to said platform at all angles of pitch, means for introducing displacements of the gun from the said vertical plane of sight and from a horizontal reference plane, and mechanism operable by both of said means for calculating and applying to the gun all of the necessary corrections in train and elevation to preserve its aim on the target throughout the roll and pitch of the platform.

2. Apparatus set forth in claim 1 in com-

bination with means for determining the pitch of the platform in the vertical plane of fire throughout all angular movements of the platform and at any angle of angular displacement of the gun relative to the vertical plane of sight.

3. In a fire control system; an unstable platform; a gun mounted to rotate thereon about train and elevation axes; a director rotatably mounted on said platform to control and correct the movements of the gun about said axes, and including means for simultaneously determining the pitch of the platform in the vertical plane of sight to the target and the roll of the platform in a plane perpendicular to said vertical plane of sight and perpendicular to said platform at all angles of pitch, a computer, settable about mutually perpendicular axes and operably connected to said means, for solving the equations:

$$\tan T = \tan E \sin R \\ \sin E_c = \sin E \cos R;$$

25 where T is the angle of correction in gun train, E_c the corrected setting in gun elevation, R the angle of cross roll, and E the angle of elevation of the gun relative to the platform uncorrected for cross roll R; and means for 30 transmitting the computed angles T and E_c to the gun to correct the movements of the gun about said axes for pitch and roll of the platform.

4. In a fire control system; an unstable 35 platform; a gun mounted to rotate thereon about train and elevation axes; a director rotatably mounted on said platform to control and correct the movements of the gun about said axes, and including means for simultaneously determining the pitch of the platform in the vertical plane of sight to the target and the roll of the platform in a plane perpendicular to said vertical plane of sight and perpendicular to said platform at all 45 angles of pitch, a computer, settable about mutually perpendicular axes and operably connected to said means, for solving the equations:

$$\tan T = \tan E \sin R + \sec E \tan Dg \cos R \\ \sin E_c = \sin E \cos Dg \cos R - \sin Dg \sin R;$$

50 where T is the angle of correction in gun train, E_c the corrected setting in gun elevation, R the angle of cross roll; E the elevation of the gun relative to the platform uncorrected for cross roll, and D_g the angle of lateral deflection of the gun bore axis relative to the vertical plane of sight to the target; and means for transmitting the computed angles T and E_c to the gun to correct the movements of the gun about said axes for pitch and roll of the platform.

5. A gun, a platform on which the gun is adjustable about elevation and train axes which vary in angular position with varia-

tions in the angular position of said platform; and means mounted to rotate on said platform about an axis fixed perpendicular thereto and settable in planes parallel to said train and elevation axes and with reference to a vertical and to a horizontal plane to control the movements of the gun about said axes and for automatically generating corrections in the movements of the gun about said axes in their various positions.

6. A gun, an angularly movable platform on which the gun is adjustable about a set of relatively fixed mutually perpendicular axes which vary in angular position with variations in the angular position of said platform; and means mounted to rotate about an axis fixed perpendicular to said platform and adapted to have corrections applied thereto in planes parallel to said axes and with reference to horizontal and vertical planes, for automatically generating, from said applied corrections, corrections in the movements of the gun about said axes, and for subsequently varying said generated corrections to compensate the movements of the gun about said axes for changes in the angular positions of said axes due to angular movements of said platform.

7. A movable support, a sighting device and a gun, each rotatable on said support about elevation and train axes; and means mounted to rotate on said support about an axis perpendicular thereto and adapted to have corrections applied thereto in planes parallel to said axes and with reference to vertical and horizontal planes, and operated by and in accordance with the movements of the said sighting device, for generating corrections in the movements of the gun about its said axes and for subsequently varying said generated corrections upon changes in the angular position of said axes due to movement of the support.

8. A movable support, a gun adjustable on said support about elevation and train axes varying in angular position with variations in the angular position of said support; and means mounted to rotate on said support about an axis perpendicular thereto and settable in planes parallel to said axes and with reference to vertical and horizontal planes, to correct the movements of the gun about said axes, and for generating the set corrections in terms of movements of the gun about said axes in their various positions, and for subsequently varying said generated corrections in response to and in proportions to changes in the angular position of said axes due to movement of said support.

9. A gun, a mount on which the gun is adjustable about elevation and train axes, a member maintained on said mount in a predetermined angular position in space independently of the inclination of the elevation

axis of the gun, a second member, means for angularly adjusting said second member relative to said mount in accordance with the range of the gun, a driving connection between said members whereby the first member is rotated, while maintained in said position in accordance with the inclination of the trunnion axis of the gun, and means for applying the rotation of the first member to the train adjustment of the gun.

10. In a fire control system; an unstable platform; a gun mounted to rotate thereon about train and elevation axes; a direction finder; an inner gimbal ring supporting said 15 finder, an outer gimbal ring pivotally supporting the inner ring, means for supporting the outer ring to rotate about an axis parallel to said platform; a computer including a base, a second pair of gimbal rings having 20 the outer ring mounted to rotate about an axis parallel to said base; means operated by maintaining horizontal the inner ring of the finder during the roll and pitch of the platform for transmitting the rotation of the inner ring of the finder directly to the outer ring of the computer and for transmitting the rotation of the outer ring of the finder directly to the inner ring of the computer; and means cooperating with the rings of the 25 computer and operable by the rotation thereof for determining and transmitting, to the gun, train and elevation settings corrected for roll and pitch of the platform.

11. In a fire control system; an unstable 30 platform; a gun mounted to rotate thereon about train and elevation axes; a director rotatably mounted on said platform to control and correct the movements of the gun about said axes, and including means for 35 simultaneously determining the pitch of the platform in the vertical plane of sight to the target and the roll of the platform in a plane perpendicular to said vertical plane of sight and perpendicular to said platform at all 40 angles of pitch, a computer, settable about mutually perpendicular axes and operably connected to said means, for solving the equation $\tan T = \tan E \sin R$; where T is the angle of correction in gun train, R is the angle of 45 cross roll, and E the angle of elevation of the gun relative to the platform uncorrected for cross roll; and means for transmitting the computed angle T to the gun to correct the 50 movements of the gun about its train axis for pitch and roll of the platform.

12. In a fire control system; an unstable 55 platform; a gun mounted to rotate thereon about train and elevation axes; a director rotatably mounted on said platform to control and correct the movements of the gun about said axes, and including means for 60 simultaneously determining the pitch of the platform in the vertical plane of sight to the target and the roll of the platform in a plane 65 perpendicular to said vertical plane of sight

and perpendicular to said platform at all angles of pitch, a computer, settable about mutually perpendicular axes and operably connected to said means, for solving the equation $\sin E_c = \sin E \cos R$; where E_c is the 70 corrected setting in gun elevation, R the angle of cross roll, and E the angle of elevation of the gun relative to the platform uncorrected for cross roll; and means for transmitting the computed angle E_c to the gun to correct the 75 movements of the gun about its elevation axis for pitch and roll of the platform.

13. In a fire control system; an unstable platform; a gun mounted to rotate thereon about train and elevation axes; a director rotatably mounted on said platform to control and correct the movements of the gun about said axes, and including means for simultaneously determining the pitch of the platform in the vertical plane of sight to the target and the roll of the platform in a plane perpendicular to said vertical plane of sight and perpendicular to said platform at all angles of pitch, a computer, settable about mutually perpendicular axes and operably connected to said means, for solving the equation: $\tan T = \tan E \sin R \sec E \tan Dg \cos R$; where T is the angle of correction in gun train, R the angle of cross roll, E the angle of elevation of the gun relative to the platform uncorrected for cross roll, and Dg the angle of lateral deflection of the gun bore axis relative to the vertical plane of sight to the target; and means for transmitting the computed angle T to the gun to correct the movements of the gun about its train axis for pitch and roll of the platform.

14. In a fire control system; an unstable platform; a gun mounted to rotate thereon about train and elevation axes; a director rotatably mounted on said platform to control and correct the movements of the gun about said axes, and including means for simultaneously determining the pitch of the platform in the vertical plane of sight to the target and the roll of the platform in a plane perpendicular to said vertical plane of sight and perpendicular to said platform at all angles of pitch, a computer, settable about mutually perpendicular axes and operably connected to said means, for solving the equation:

$$\sin E_c = \sin E \cos Dg \cos R - \sin Dg \sin R;$$

where E_c is the corrected setting in gun elevation, R the angle of cross roll, E the angle of elevation of the gun relative to the platform uncorrected for cross roll, and Dg the angle of lateral deflection of the gun bore axis relative to the vertical plane of sight to the target; and means for transmitting the computed angle E_c to the gun to correct the movements of the gun about its elevation axis for pitch and roll of the platform.

15. An unstable platform, a gun mounted

- to rotate thereon about the usual train and elevation axes, and a fire control director mounted to rotate on said platform about an axis parallel to the train axis of the gun, said director including: means for determining the direction of a target from the intersection of said train and elevation axes; and means for simultaneously determining the inclination of the platform to the horizontal
- 5 10 in the vertical plane through said intersection and target, and the inclination of the platform to the horizontal in the vertical plane of fire of the gun at all angles of deflection of the gun relative to the first named plane.
- 15 16. An unstable platform, a gun mounted to rotate thereon about the usual train and elevation axes, and a fire control director mounted to rotate on said platform about an axis parallel to the train axis of the gun, said
- 20 director including: means for determining the direction of a target from the intersection of said train and elevation axes; and means for simultaneously determining the inclination of the platform to the horizontal
- 23 25 in the vertical plane through said intersection and target, the inclination of the platform to the horizontal in a plane passing through said intersection and perpendicular to said platform and to said vertical plane
- 30 at all inclinations of said platform in said vertical plane, and the inclination of the platform to the horizontal in the vertical plane of fire of the gun at all angles of deflection of the gun relative to the first named plane.
- 35 17. In a continuous aim fire control system, an unstable platform, a support rotatable on said platform about an axis perpendicular thereto, an outer gimbal ring mounted to rotate on said support about an axis
- 40 parallel to said platform, an inner ring mounted to rotate in the outer ring about an axis perpendicular to the axis of rotation of the outer ring, a target telescope mounted to rotate on said inner ring about an axis parallel to the axis of rotation of the inner ring
- 45 in the outer ring, two telescopes arranged at a substantial angle to each other on the inner ring with their lines of sight parallel to the plane of said inner ring, and means controlled
- 50 by the movements of the target telescope while held trained on a target at any location in space and by holding the two telescopes trained on the horizon or distant objects to correct all of the trunnion tilt errors in the
- 55 train and elevation settings of a gun mounted to rotate about train and elevation axes on said platform.

In testimony whereof I affix my signature.
JOSEPH DUGAN.
